UNITED STATES PATENT OFFICE.

HOWARD B. VANNOTE, OF HASBROUCK HEIGHTS, NEW JERSEY.

BAG-HOLDER.

1,149,604.

Specification of Letters Patent. Patented Aug. 10, 1915.

Application filed September 29, 1914. Serial No. 864,077.

To all whom it may concern:

Be it known that I, HOWARD B. VANNOTE, a citizen of the United States, and a resident of Hasbrouck Heights, in the county 5 of Bergen and State of New Jersey, have invented a new and Improved Bag-Holder, of which the following is a full, clear, and exact description.

This invention relates to bag holders or 10 supports and has particular reference to devices of this character adapted for holding mail bags in post offices, railway mail cars or the like.

Among the objects of the invention is to 15 provide a construction suitable for holding in a convenient position a considerable number of individual bags, the construction being of maximum simplicity and strength.

Another object of the invention is to increase the facility for assembling the device 20 or for replacing bent or broken parts.

The foregoing and other objects of the invention will hereinafter be more fully described and claimed and illustrated in the 25 drawings forming a part of this specification in which like characters of reference indicate corresponding parts in all the views, and in which—

Figure 1 is a plan view of a preferred 30 embodiment of this invention, the rack being adapted to support ten mail bags; Fig. 2 is a front elevation of the same; Fig. 3 is a right hand end elevation; Fig. 4 is a vertical section on the line 4—4 of Fig. 1, 35 showing the peculiar clamp adapted to secure two frame members at right angles to each other in a peculiar manner; and Fig. 5 is a perspective view of the clamp members detached.

The several parts of this device may be 40 made of any suitable materials, and the relative sizes and proportions, as well as the general design of the mechanism, may be varied to a considerable extent without departing from the spirit of the invention 45 hereinafter more fully described and specifically claimed.

Referring more particularly to the drawings, I show at 10 a substantially rectangular frame member comprising a central longitudinal rib 11 extending the full length of the frame. This rib is indicated as being constructed of gas pipe or other similar hollow cylindrical material; hence comprising maximum strength and cheapness.

At 12 I show a series, shown as six in

number, of transverse members arranged parallel to one another in the same plane. Each of these members is locked rigidly by a detachable clamp 13 directly in gripping 60 contact with and at right angles to the central rib 11.

Along the front edge of the frame is provided a connecting bar 14 and at the rear edge is another similar bar 15, both 65 preferably parallel to the rib 11, and connected to the ends of all of the cross bars 12 by T-couplings 16 or angle couplings 17. These couplings may be connected to the cross bars by screw threads or other suitable means and the front and rear connecting bars 14 and 15 are fitted in the T-couplings as well as in the angle couplings, making a rigid frame 10 and providing in the preferred form of the 70 structure ten rectangular openings or spaces for as many individual bags to be suspended therebeneath. At the four corners of each of said spaces are arranged suitable means for suspending a mail bag 80 with its mouth open. This means is shown as a plurality of hooks 18 each pivotally mounted upon a cross bar 12, each hook member comprising a ring or eye 19, a hook proper 20, and a finger piece 21 whereby the 85 hook may be manipulated for engaging or disengaging a mail bag. The several hooks, while free to rotate around the cross bars, are held from longitudinal movement thereon adjacent the couplings and clamps by 90 means of pins 22 or equivalent means.

Each of the clamps 13 comprises upper and lower parts 23 and 24. These clamp members are substantially square in plan and each includes a semi-cylindrical socket 95 member 25 and flat side flanges 26. Each socket member is deep enough to receive one of the bars, one socket member of the part 23 being adapted to receive the cross bar 12, and the similar part of the other clamp 100 member receiving the rib 11. The relative sizes of the parts, however, are such that when the two clamp members 23 and 24 are brought together with the flanges 26 adjacent each other, the two perpendicularly arranged frame members will bear firmly against each other and will be gripped in such position by the action of the fastening means 27 passing through adjacent corners of the clamp members. By providing the 110 socket members 25 of slightly less depth than the diameter of the parts to be received

therein, said parts may be caused to bind firmly upon each other when the bolts or rivets 27 are acted upon to lock the clamp members in coöperation with each other.

5 Any suitable means may be provided to support the frame 10. For this purpose, however, I provide special clamp members 24' for coöperation with the corresponding members 23' for coöperation with the cross bars 12 next to the end bars at both ends of the frame. In other words, while I construct a rack or support providing for ten bags, six of such bags will be supported between the two clamp members 13' and the 10 other four will be supported on the outside of such clamps or two at each end of the frame. By this arrangement I provide maximum rigidity and strength for the device. A pair of standards 28 are connected 15 to the clamp members 24' with their axes perpendicular to the axis of the rib 11, but at such an oblique angle to the axes of the bars 12 as to provide a slight inclination downwardly and forwardly of the frame 10 as indicated in Figs 2 and 3. This arrangement facilitates the operation of sorting mail. Each standard 28 is supported upon 20 a foot 29 made in any suitable manner and supported upon casters 30.

30 I claim:

1. The herein described bag holder comprising, in combination, a central rib of uniform cross section, a series of cross bars arranged in contact with the rib and at right 35 angles thereto, a series of clamps coöperating with said cross bars and rib, each clamp comprising a pair of coöoperating members, each member having a socket to receive a part to be gripped thereby, and means to 40 cause the clamp members to approach each other forcibly, causing the perpendicularly arranged members to be gripped strongly to each other.

2. In a bag holder, the combination of a 45 frame comprising longitudinal and transverse bars each of uniform cross section throughout its length, all of said bars ex-

tending from one edge of the frame to the opposite edge, coupling members connecting the longitudinal and transverse bars to one another at right angles, said coupling devices including two-part clamps having socket members to receive the parts to be coupled and means to cause the clamp members to approach each other forcibly to cause the adjacent parts to be gripped against each other, and means to support the frame, substantially as set forth.

3. In a bag holder, the combination of front and rear longitudinal bars arranged in the same plane, a central longitudinal rib parallel to the first bars but below the plane thereof, a series of cross bars arranged in the same plane as the front and rear bars, means to connect said cross bars and front and rear bars, the cross bars lying in direct contact with the upper surface of the central bar, and binding members coöperating with the cross bars and central bar causing them to forcibly grip each other.

4. In a bag holder, the combination of a frame comprising front and rear connecting bars, a series of cross bars extending between and in the same plane as the connecting bars, means to connect all of said bars 75 together, a central rib parallel to the connecting bars and immediately below the plane thereof and in direct contact with the lower edges of the cross bars, two-part clamps connecting the cross bars with the 80 central rib causing the same to bind firmly upon one another, bag holding devices connected to the frame, and supports for the frame including a pair of standards secured to the two-part clamps adjacent the end 85 clamps of the series, substantially as set forth.

In testimony whereof I have signed my name to this specification in the presence of two subscribing witnesses.

HOWARD B. VANNOTE.
